WRITING IMPLEMENT CONTAINER

Wing G. Lew, Los Angeles, Calif., assignor to Decolage,
Inc., Los Angeles, Calif., a corporation of California

Filed Jan. 2, 1969, Ser. No. 15,172

Term of patent 14 years

Int. Cl. D19—02
U.S. Cl. D74—5

FIG. 2 is a side elevation thereof looking in the direction of arrow 2 of FIG. 1;

FIG. 3 is a top plan view thereof; and

FIG. 4 is a side elevation thereof looking in the direction of arrow 4 of FIG. 1.

The bottom is substantially plain and unornamented.

I claim:

The ornamental design for a writing implement container, substantially as shown and described.
